UNITED STATES PATENT OFFICE

WILLIAM B. ALLBRIGHT, OF CHICAGO, ILLINOIS.

FLEXIBLE BEATER.

1,071,017.

Specification of Letters Patent.

Patented Aug. 26, 1913.

Application filed February 12, 1912. Serial No. 677,108.

To all whom it may concern:

Be it known that I, WILLIAM B. ALLBRIGHT, a citizen of the United States, and a resident of the city of Chicago, in the county of Cook and State of Illinois, have invented certain new and useful Improvements in Flexible Beaters; and I do hereby declare that the following is a full, clear, and exact description of the same, reference 10 being had to the accompanying drawings, and to the numbers of reference marked thereon, which form a part of this specification.

This invention relates to improvements in 15 flexible beaters of that class intended to be secured on a rotatable shaft for operating the same, as, for example, in a machine for dehairing carcasses. Such beaters have heretofore been constructed of canvas or 20 rubber belting bent to afford a loop, and the ends thereof secured to the shaft. Where such beaters are used in machines for dehairing hogs, the service is exceedingly heavy, inasmuch as sometimes six or seven 25 hundred hogs per hour are passed through such machines and subjected at the same time to the action of said beaters in the presence of a constant spray of hot water and steam, and in consequence, the beaters 30 lose much of their resiliency, and although dehairing the carcass, they may injure it owing to the character of the blow struck by the beater because of its loss of resiliency. Not only so, such loss of resiliency greatly 35 decreases the life of the beater and causes the same to soon wear out and necessitate replacement.

The object of this invention is to afford a 40 construction whereby a resilient member is provided between, and connecting the sides of a beater at about the middle thereof, and by means of which the beater is reinforced at about its middle, or, in other words, at or 45 near the place where the beater most usually shows sign of weakness.

It is also an object of the invention to 50 greatly increase the resiliency of such beaters near the middle thereof without materially increasing the weight of the same.

It is a further object of the invention to 55 afford a construction adapted for use and embodiment in lieu of any of the beaters heretofore used in machines of the kind, without material additional expense, and to afford a construction whereby shorter

lengths of the material of which the beaters are constructed may be employed to advantage.

It is, of course, an object of the invention to afford a reinforced, resilient and looped 60 beater for any purpose whatsoever that the same may be useful, and to afford a strong, durable and effective device of the class specified.

The invention in its preferred form, is 65 hereinafter more fully described.

In the drawings: Figure 1 is a perspective view of a device embodying my invention, showing the opposite ends of the looped beaters on opposite sides of the shaft. 70 Fig. 2 is a similar view illustrating a very slightly modified construction, and with the opposite ends of each individual looped beater secured on the same side of the shaft. Fig. 3 is a fragmentary section taken longitudinally of the shaft at the point of connection of the beaters therewith, as shown in Fig. 1. Fig. 4 is a similar view with reference to Fig. 2.

As shown in the drawings: 1, indicates the 80 shaft, and referring to Figs. 1 and 3, 2, indicates a relatively short looped resilient member of rubber or canvas belting, or any suitable material having the ends bent into parallel relation and each overlapped with 85 the corresponding ends of an oppositely disposed loop 2, and secured between short pieces of belting 3, which rest thereon to reinforce the same from short bending on the shaft, and above which is a plate 4, having a curved forward edge 5, over which the beater may be slightly bent. 6, indicates the 90 beater proper, comprising a piece of rubber or canvas belting or other suitable material, of suitable width and ply bent to form a 95 loop and the ends of which are riveted or otherwise permanently secured on each side of the bend of the loops 2, so that the bend of the loop 2, lies between the arms of the loop 6, and is riveted centrally therebetween 100 to afford a resilient arching bridge member.

The construction illustrated in Figs. 2 and 4, is substantially the same excepting that the outer loop or beater proper 7, is riveted on one (the outer) side of the inner loop 8, and the other end thereof is carried beneath the same and riveted thereto, as shown in Fig. 2, and thence secured on the shaft 1. As shown, the ends of said beaters are secured on the same side of the shaft for any 11

individual beater. The inner end 9, of the loop 7, extends between the ends 10, of the beater 8, and the shaft 1, and is engaged in place by means of a piece of belting 12, corresponding with the piece of belting 3, before described, and upon which is placed a plate 4, and as shown bolts 13, extend through the same and the like assemblage at the opposite side of the shaft for the oppositely disposed beaters and rigidly engage all of the members in proper position. At the outer end of said beaters directed toward the front side thereof, are slightly curved scraping blades 14. These may vary in size and number, dependent upon the use to which the machine is to be put.

The operation is as follows: When the shaft is rotated, said beaters are held outwardly centrifugally and the scalded carcasses passing the same are successively and rapidly struck thereby, quickly removing all hair therefrom and at the same time in effect massaging the skin or hide to remove all dirt from the pores of the skin. As each blow is struck by the beater, the beater, of course, is temporarily held by engagement with the carcass until the rotation of the shaft on which the beaters are secured, serves to carry the beaters past the carcass, of necessity bending the beaters reversely in so doing, such bending occurring mostly heretofore at about the points occupied by the loops of the inner or reinforcing beaters. Such reinforcing loops, however, serve to tie the sides of the beater yieldingly in relation with each other, so that, instead of bending at said point only, the beater appears to bend as a whole, and is immediately thrown outwardly again to operative position, aided in part by the resiliency of the inner loop. In consequence of this resiliency and the yielding pressure at all times exerted by said inner loop on the beater, the carcasses are much more effectively scraped or cleaned, and the life of the beater is greatly increased and extended.

As shown in Figs. 1 and 2, the beaters are provided with a plurality of apertures 15 adapted to permit the increase or decrease in the length of the beater by the securing of the bolts 13, therethrough. When the beater is first put in use it is connected to the shaft 1, by means of the bolts 13, which extend through the apertures in the ends of the beaters. After a considerable period of use the beater becomes somewhat elongated and may be again adjusted to a position most effective for operation by engaging the same on the shaft by inner series of apertures 15 as shown in Figs. 1 and 2.

In the construction illustrated in Fig. 2, a somewhat stronger construction is afforded, inasmuch as a double layer of the fabric of which the beater is composed, is extended back to, and rigidly secured on the shaft at

that side of the beater upon which the pull is directed during the reverse bending thereof when at work.

Of course, I am aware that the bridging or reinforcing member may be inserted in various ways within the outer loop or beater to increase and retain resiliency. I have shown but the preferred of several different possible constructions for the purpose specified, and I therefore do not purpose limiting the patent granted on this invention otherwise than necessitated by the prior art.

I claim as my invention:

1. A beater of the class described, embracing a loop of flexible material, and a reinforcing looped web disposed within but short of the end of said outer loop.

2. A beater of the class described, embracing a strip of material bent to form an inner loop and adapted to be rigidly secured to a shaft, and an outer longer loop of suitable material fastened at its ends in fixed relation with respect to said inner loop.

3. A beater of the class described, embracing a strip of material bent to afford an inner loop and rigidly secured at its ends upon a shaft, and an outer loop of material having its ends riveted to each side of said inner loop, said inner loop affording a transverse connection therebetween.

4. A beater of the class described, embracing a strip of fabric such as belting bent to afford an inner loop and adapted to be rigidly secured with the ends of the fabric upon a shaft, an outer loop of similar material having its ends riveted on each side the inner loop, said inner loop affording a transverse connection therebetween, and scraping means secured on the outer loop.

5. A beater of the class described, comprising a strip of canvas belting bent to afford a loop with its ends rigidly bolted to a shaft, and an outer beater comprising a strip of similar fabric likewise bent to afford a loop and with its ends riveted to, and inclosing the bend of the inner beater.

6. A centrifugally acting beater for dehauling carcasses, embracing in combination with a rotative shaft, of a strip of fabric such as belting bent to afford a loop and rigidly bolted to the shaft at an angle therewith to act centrifugally therefrom with the rotation thereof, and a strip of similar fabric bent to afford a longer loop and at one end riveted to the first named loop at one side thereof and at the other extending beneath the other side of said loop and secured to the shaft therewith.

7. The combination with a rotative shaft, of a strip of fabric bent to afford a loop and rigidly secured at its ends to said shaft, and a similar strip of looped fabric inclosing and extending beyond said inner loop

and at its ends rigidly secured to opposite sides of said inner loop, said inner loop affording a convexly curved tie member at about the middle of the beater considered 5 as a whole.

8. A beater of the class described, comprising resilient and flexible strips connected to afford a loop, and an inner shorter looped resilient member connecting the 10 sides of said outer loop near the middle thereof.

9. A looped beater of the class described, embracing a strip of fabric bent to afford an inner loop and adapted to be rigidly secured upon a shaft, and an outer longer 15 loop of similar material having its ends secured on each side the inner loop.

10. A centrifugally acting beater for dehairing carcasses, embracing in combination 20 with a rotative shaft, a loop of fabric rigidly secured to the shaft to act centrifugally therefrom with the rotation thereof, and a strip of similar fabric bent to afford a longer loop and at one end secured to the 25 first named loop at one side thereof and at the other secured to the shaft.

11. The combination with a rotative shaft, of a strip of fabric bent to afford a loop and adjustably secured at its ends to the 30 shaft, and a similar looped strip of fabric inclosing and extending beyond said loop and at the ends thereof adjustably secured on opposite sides thereof.

12. The combination with a rotative shaft, of a plurality of looped beaters, and a 35 shorter looped member within each of said looped beaters adapted to reinforce said beaters and hold the same normally distended.

13. A centrifugally acting beater for dehairing carcasses, embracing in combination 40 with a rotative shaft, a looped flexible strip of fabric rigidly secured to said shaft to act centrifugally therefrom with the rotation thereof, and a strip of similar fabric 45 secured to said shaft and to the first named strip and bent to afford a shorter loop adapted to reinforce the first strip and prevent short bending of the same.

14. A beater for dehauling carcasses, embracing in combination with a rotative element, a looped strip of flexible material secured thereto to act with the rotation thereof, and a second strip of flexible material secured to said element and to the first 55 named strip and bent to afford a shorter loop adapted to prevent short bending of the first named strip.

In testimony whereof I have hereunto subscribed my name in the presence of two 60 subscribing witnesses.
